CRANK ASSEMBLY

John S. Sharpe, Haverford, Pa.

Application January 16, 1941, Serial No. 374,763

3 Claims. (Cl. 74—580)

A principal object of this invention is to provide an improved form of crank assembly for combustion engines, said assembly incorporating adjustable means for varying the compression ratio of the engine cylinder or cylinders.

Another object of the invention is to provide an improved "true stroke" crank assembly primarily for combustion engines of the radial type, said assembly eliminating the necessity for the conventional master rod and affording a substantially uniform distribution of thrusts imposed upon the crank shaft from the pistons.

Still another object of the invention is to provide an improved crank assembly for combustion engines of the radial type which shall combine the desirable true stroke characteristics with means for varying the compression ratio of the respective cylinders.

A still further object of the invention is to provide a variable compression crank assembly having improved means for regulating the timing of the ignition and of the valves in accordance with the variations in compression ratio.

The invention further resides in the novel structural details and arrangements hereinafter described and illustrated in the attached drawings, wherein

Figure 1 is a vertical sectional view showing a crank assembly of a combustion engine of the radial type made in accordance with my invention;

Fig. 2 is a section on the line 2—2, Fig. 1;

Figs. 3, 4, 5 and 6 are diagrammatic views illustrating certain characteristics of the mechanism shown in Figs. 1 and 2;

Fig. 7 is a diagrammatic view showing a radial engine comprising a crank assembly made in accordance with the invention;

Fig. 8 is a view illustrating the mechanical details of the engine assembly, including the various control elements associated with the crank unit, and

Fig. 9 is a view corresponding to Fig. 1 and illustrating a modification within the scope of the invention.

With reference particularly to Figs. 1 and 2, 1 is the crank case of a radial engine and 2 the cylinders. Journalized in the crank case upon bearings 3 and 4 is a crank shaft 5, the crank 6 of which is counterbalanced by weights 7, 7. Journalized on the crank pin is a connecting rod member 8 to which are pivotally secured, through the medium of wrist pins 9, the connecting rods 11 of the several pistons which operate in the usual manner within the cylinders 2. In Figs. 55

3 and 5, the pistons are designated by the reference numeral 12. Thus the pistons are operatively connected to the crank shaft through the intermediate member 8, which, as previously set forth, is journaled on the crank 6.

The member 8 comprises an internal gear 13 concentric with the axis of the crank pin 6. The gear 13 meshes with a gear 14 which is journaled on bearings 15 on the arm 6a of the crank. The gear 14 meshes also with an internal gear 16 which is of the same pitch diameter as the gear 13 and is supported in the casing 1, as hereinafter described, concentrically with the axis of the shaft 5. Both of the internal gears 13 and 16 are beveled, and the gear 14, which may be in the form of a simple spur, is correspondingly inclined to the axis of the shaft 5. The teeth of the gears 13 and 16 are formed by known method to function efficiently with the teeth of the spur gear 14. The effect of the geared connection between the member 8 and the casing is to maintain the member 8 substantially fixed with respect to its own axis on the crank 6 while permitting the member 8 to move bodily in the annular path described by the crank. Thus the torque thrusts from the several pistons are transmitted through the connecting rods 11 and the member 8 to the crank 6 with substantial uniformity, the entire assembly being accurately balanced with respect to said thrusts and being free from the unbalanced forces and resulting vibrations which are inherent in the conventional assembly employing a master rod.

The gear 16 is supported in the casing 1 in a manner to permit of the angular adjustment of this gear about its own axis, which as previously set forth corresponds to the axis of the shaft 5. In the present instance, the gear is provided with a peripheral flange 17 which is fitted accurately into a recessed seat in the inner wall of the casing, as best illustrated in Fig. 1, and a ring 18 secured to the said wall by screws 19 overlies the inner face of the flange and thereby retains the gear in place within said recess. The gear 16 is provided also with a boss 21 which extends through a slotted port 22 in the wall of the casing 1, and this boss has secured to the outer end thereof, by means of screws 23, a segmental worm wheel 24. The worm wheel meshes with a worm 25 which is fixed to a shaft 26 supported in journals 27 and 28 on the casing 1, see Fig. 2. One end of the shaft carries a bevel pinion 29 which meshes with a pinion 30 carried by a shaft 31 suitably journaled in the casing, and the shaft 31 is connected to a suitable manual or other actuator,

as hereinafter described. It will be apparent that actuation of the worm 25 will effect an angular adjustment about its axis of the gear 16, and through the intermediate gear 14 of the gear 13 and of the member 8 of which this latter gear forms a part. Angular adjustment of the member 8 with respect to its axis in the crank 6 will effect an adjustment of the pistons 12 in their respective cylinders, and this adjustment of the pistons will be uniform.

The adjustment of the parts as described is best illustrated in Figs. 3 to 6, inclusive. If it be assumed that originally the parts are as shown in Fig. 3, wherein at the top of the piston stroke the connecting rod 11 is in line with the longitudinal axis of the cylinder, and wherein further the axes of the shaft 5 and of the crank 6 occupy a common plane which includes the longitudinal center line of the cylinder, then each of the wrist pins 9 which connect the respective connecting rods to the member 8 will, as the crank shaft rotates, move in a circle the center of which is also intersected by said plane. This is the condition of maximum compression within the respective cylinders.

With reference to Figs. 3 and 4, *a* represents the axis of the shaft 5 and *b* the axis of the crank 6. Under the circumstances described, the center of the wrist pin 9 will describe a circular path indicated at *c*. In Fig. 4, the relative position of the gears 13, 14 and 16, corresponding to the position of the gears shown in Fig. 3 and described above, is illustrated. Let us assume now that the gear 16 is adjusted through the medium of the worm 25 as previously described through an angle *x* shown in Fig. 6. In this movement of the gear 16, the point *d*, Fig. 4, will move to the position in which it is shown in Fig. 6. Similarly the gear 13 will be adjusted in the same direction through a corresponding angle *x'* so that the point *e* in Fig. 4 will move to the position shown in Fig. 6. As a result of this movement of the gears, the member 8 will be adjusted about the axis *b* of the crank 6 through an angle, see Fig. 5, corresponding to the angular movement of the gear 13, as indicated by the same reference character in Fig. 6. As a result of this angular movement of the member 8, the piston 12 will be retracted in its cylinder to the extent illustrated in Fig. 5, and also as a result of the aforescribed adjustment, the wrist pin 9 will, as the crank shaft rotates, describe a path indicated in Fig. 5 by the circle *c'*. In this movement of the wrist pin 9, the piston will reach the top of its stroke when the piston rod 11 extends radially to the circle *c'*, as indicated by the line *g* in Fig. 5. It will be apparent that by reason of the aforescribed adjustment, the piston 12 at the top of its stroke will approach less closely to the cylinder head than in the original adjustment of the parts illustrated in Fig. 3, and that, therefore, the compression ratio in the cylinder will be materially reduced. It will be understood that adjustment of the member 8 as described affects the compression in each of the cylinders of the engine to exactly the same extent.

It will be noted by reference to Figs. 3 and 5 that the adjustment of the parts as previously set forth results also in a change in the relation between the movement of the crank shaft and the stroke of the piston. Thus when the parts are as illustrated in Figs. 3 and 4, the piston 12 reaches the top of its stroke at the moment when the crank 6, as indicated by the letter *b*, lies in closest proximity to or on the longitudinal axis

of the engine cylinder. After the adjustment illustrated in Figs. 5 and 6, however, it will be noted that when the axis of the crank *b* occupies this same relative position, the piston 12 has not reached the top of its stroke, since the connecting rod 11 lies slightly out of alignment with the radial line *g* extending from the center of the circle *c'*. The wrist pin 9 must, therefore, move through the small angle between the point *h* and the line *g* before the piston 12 reaches the top of its stroke. Assuming, therefore, that the ignition is timed so as to create the spark in the cylinder at the time that the parts occupy the relative positions illustrated in Fig. 3, at which time the piston is at the top of its stroke, then this timing, if maintained, would result, after adjustment of the parts as illustrated in Figs. 5 and 6, in the creation of the spark slightly in advance of the top of the piston stroke. If it be desired to maintain the original relative timing, therefore, adjustment must be made, through the distributor for example, for delaying or retarding the spark until after the axis *b* of the crank 6 shall have moved slightly beyond the positions in which it is shown in Figs. 3 and 5.

In Figs. 2 and 8, I have illustrated diagrammatically a means for adjusting the timing of the ignition in accordance with adjustments in the compression ratio as described above and in direct relation to the extent of such adjustment so that the timing of the ignition may remain relatively the same under all conditions of compression adjustment. It will be noted by reference to Fig. 2 that the shaft 26, which carries the worm 25 as previously described, carries also at one end a worm 32 which meshes with a segmental worm wheel 33 on a shaft 34 suitably journaled in the casing. Referring now to Fig. 8, it will be noted that the shaft 34 carries a cam 35 which is operatively connected through a bell crank lever 36 with the adjustable head 37 of the distributor 38, this distributor being operatively connected in the conventional manner with the crank shaft 5 through the medium of bevel gears 39 and 41. With this arrangement, any adjustment of the elements of the crank assembly, through the medium of the worm 25 as previously described, will result in an adjustment of the distributor 38, and the cam 35 may be so formed that the adjustment of the distributor to retard or advance the ignition spark will be such as to correct or to compensate for the maladjustment between the crank movement and the piston stroke resulting from the aforescribed compression adjustment.

A similar compensating adjustment of the timing of the valves may be effected through the shaft 34, as illustrated in Fig. 8. In this case, the valve-actuating cam 42 is journaled freely on the crank shaft 5, and is rotated in timed relation with the rotation of the crank shaft through gears 43 and 44 and a pinion 45 directly connected with the gear 44 and meshing with an internal gear 46 in the cam ring 42. 47 and 48 constitute the rods which operatively connect the valves (not shown) with the cam 42. The shaft 49, which carries the gears 44 and 45, is in this instance mounted upon an arm 51 which is pivotally supported at its inner end upon the crank shaft 5 and which has at its outer end a rack 52 which meshes with a suitable gear element 53 on the shaft 34. With this arrangement, any adjustment of the shaft 34 will cause a swinging of the arm 51 about the axis of the shaft 5 and a corresponding adjustment of the gears 44 and 45

angularly with respect to the shaft axis. This results in a corresponding angular adjustment of the cam 42 about the same axis and a resulting relative adjustment of the timing of the valves compensating the maladjustment previously referred to.

It will be noted by reference to Fig. 2 that I have provided at each end of the slot 22 a stop, 54 and 55 respectively, which by engagement with the ends of the segmental worm wheel 24 limits the angular adjustment of the gear 16. Preferably, these stops 54 and 55, as illustrated, are adjustable, so that the actual extent of the maximum adjustment of the gear wheel 16 may be regulated as required.

The shaft 31, which carries the bevel pinion 30, may as previously set forth be connected to any desired form of actuator, and in Fig. 7, I have illustrated this shaft as connected through a rod 56 and universal joints 57 and 58 with a shaft 59 carrying a hand wheel 61, thus providing for adjustment of the parts as described from a point remote to the engine 62, which in this case is shown as an aircraft motor.

In Fig. 9, I have illustrated a crank assembly corresponding in all essential respects with that previously described and illustrated in Fig. 1, with the exception that the gears 13a and 16a are in this case not beveled as in the previously described embodiment, the gear 14 of the latter embodiment being replaced in this case by a gear 14a which operates in planes normal to the axis of the crank shaft 5a. In all other respects and in the mode of operation the assembly is the same.

While the crank assembly is of primary interest in connection with combustion engines, as herein described, it is applicable also to other mechanisms, such, for example, as pumps, and there is to be no limitation in this respect.

I claim:

1. In a crank assembly, a shaft having a crank, a connecting rod member journaled on and com-

prising an internal gear concentric with the crank pin, a relatively fixed internal gear concentric with the shaft axis, and a planetary gear element journaled on the crank shaft eccentrically to the axis of the shaft and of the crank pin and engaged with both of said internal gears, said planetary element occupying a plane inclined to the axes of the shaft and the crank pin and being operative to maintain a substantially fixed angular relation between said gears.

2. In a crank assembly, a casing, a shaft journaled in said casing and having a crank, a connecting rod member journaled on said crank and comprising an internal gear concentric with the crank pin, a relatively fixed internal gear of the same pitch diameter mounted on said casing concentrically with the shaft axis, and a planetary gear element journaled on the crank shaft eccentrically to the axes of the shaft and of the crank pin and engaged with said internal gears, said planetary element being operative to maintain the first named of said internal gears in substantially fixed angular relation with the second-named internal gear.

3. In a crank assembly, a casing, a shaft journaled in said casing and having a crank, a connecting rod member journaled on said crank and comprising an internal gear concentric with the crank pin, a relatively fixed internal gear of the same pitch diameter mounted on said casing concentrically with the shaft axis, a planetary gear element journaled on the crank shaft eccentrically to the axes of the shaft and of the crank pin and engaged with said internal gears, said planetary element being operative to maintain the first named of said internal gears in substantially fixed angular relation with the second-named internal gear, and means for adjusting said second-named gear angularly about the axis of said shaft.

JOHN S. SHARPE.
